POLARIZED RELAY SWITCH

Edward M. Ashworth and Frank F. Ambuhl, Toronto, Ontario, Canada, assignors to Toronto Electric Commissions, Toronto, Ontario, Canada

Application December 17, 1931
Serial No. 581,658

4 Claims. (Cl. 175—339)

The principal objects of the invention are to provide a relay switch which may be operated by an extremely small current so that a considerable number of such devices may be connected to 5 a common source of power to be operated simultaneously.

A further important object is to devise a relay of the polarized type having a strong and reliable operating movement to effect the operation of a 10 circuit making and breaking device, and which may be manufactured at a comparatively low cost.

The principal feature of the invention consists in the novel construction of a magnetic device 15 whereby a moveable switch operating element is arranged in operating association with a permanent magnet and an electro-magnet, the latter being adapted to effect an increase in the magnetic flux of either pole of the magnet to cause 20 the operation of the armature.

In the drawing, Figure 1 is an elevational dia- 25 grammatical view of a structure adapted for carrying this invention into effect.

Figure 2 is a side elevational view of the device 30 illustrated in Figure 1.

Figure 3 is an elevational view of the device from the opposite side to the view illustrated in 35 Figure 1 and showing the switch contacts.

In the operation of electric signs, water heating 40 devices and other electrical operating appliances it is frequently desirable that such devices be controlled from some central point.

Numerous forms of distant control apparatus for accomplishing this result are known but they 45 are both expensive to construct and require considerable current to operate and are therefore difficult to maintain in operating service as well as being expensive.

According to the present invention the device 50 illustrated in Figure 1 consists of a permanent U-shaped steel magnet 1 upon which is arranged a central pole or core 2 of soft steel or iron which is rigidly secured thereto, as here shown, by a screw 3 which also connects the magnet 1 to a 55 base 4.

A magnet coil 5 encircles the core 2.

A yoke, preferably formed of a pair of plates 6, secured to end blocks 7 is clamped across the ends of the U magnet 1 and a spindle 8 is rotatably 60 mounted centrally of said yoke.

An armature 9 is rigidly secured to the spindle 65 between the side plates 6 of the yoke and it is provided with curved ends 10 concentric with the spindle 8 and these ends are arranged to 70 swing in close association with the similarly

curved surfaces of the ends of the magnet 1 on the pivot of the armature.

The armature is also provided with a centrally arranged concentric portion 12 midway of its length adapted to swing in close association with the similarly curved end 13 of the soft iron core 2.

A plate 14 preferably comprising a strip of steel is secured to the upper side of the armature and is provided with copper or other suitable non-magnetic buffer pieces 15.

The magnet coil 5 is here shown connected to a two-wire direct current source of supply 16 and is controlled by the use of a double throw reversing switch 17, by means of which the polarity of the current flowing through the coil may 70 be changed. It may be found desirable to operate this device on a single wire control, which on account of the low current value, may be utilized with a grounded circuit.

When the relay coil is energized with polarity, 75 as illustrated in Figure 1, and, assuming the poles of the magnet 1 with a polarity as indicated, the magnetism or lines of force will be caused to flow in the same direction in the centre core and the right hand "plus pole" A 80 and in the opposite or "minus" direction in the left hand minus pole B. The magnetic flux in the pole B is approximately equal to the sum of the fluxes in the centre pole and the pole A, thereby causing the armature to be pulled 85 down toward the pole B until the over-hanging end of the flat steel plate or strip 14 engages the top of the armature coming into mechanical contact with the end of the pole B. The armature is then held in this position by virtue of 90 the magnetic flux of the permanent pole B until the polarity of the operating coil is reversed, causing the armature to be pulled down on the side of the pole A. The copper bands 15 arranged on the ends of the steel strip or plate 95 14 of the magnet prevent the relay sticking in either one position or the other, and the presence of the overhanging steel strip 14 assists materially in the operation of the armature from one side to the other and tends to maintain the position 100 of the armature after it has operated until the polarity of the operating coil is again changed.

Mounted on the spindle 8 is a disc 18 upon the outer face of which are secured two pairs of contact plates 19 and 20. These plates are 105 separated from each other and one of the pair of plates 19 is connected to the opposite one of the pair of plates 20 by a cross connecting bar 21 arranged on the back of the disc.

A contact block 22 is secured to the base 4 110

and carries the contacts 23 and 24 connected to the coil 5. It also carries a pair of spring contact fingers 26 and 27 arranged one at each end and extending vertically upward to engage the 5 contact plates 19 and 20 of the disc 18.

The upper ends of these contact fingers 26 and 27 are preferably provided with suitable brushes to ensure ease and smoothness of operation.

10 Circuit contacts 28 and 29 are arranged on the brushes at the base and are connected to suitable service wires connecting with an operating mechanism which it is desired to control.

15 It will be seen that when the current is directed in accordance with a selected polarity through the coil 1, the armature may be manipulated to be moved to either one side or the other and thereby move into engagement with the brushes of the finger contacts a plate forming a closed 20 connection between said fingers so that an operating circuit will be closed, or when the polarity of the control circuit is altered the armature will be operated to rotate the spindle and disc 18 carried thereby to open the operating circuit.

25 A device such as described will operate on an extremely small current which may be defined as measured in milliamperes, consequently a great number of these relay devices may be operated from a single circuit. This enables electrical 30 power companies to sell current on "off peak" loads for special purposes, such as operating electric water heaters and other devices which may be utilized to advantage with intermittent current supply and by the use of a low current, or 35 a normal amount of current over a supply system an entire block of relay devices may be operated.

What we claim as our invention is:—

1. A polarized relay comprising a permanent 40 U-magnet, an armature rotatably mounted between the poles of said magnet and having a protuberance intermediate of its length presenting a surface concentric with the armature axis,

and an electro-magnet mounted within said U-magnet and having a core terminating in a curved surface concentric with the concentric surface of the protuberance of the armature in close influential relation thereto, said electro-magnet being adapted to be selectively energized to effect rotation of the armature in either direction.

2. A polarized relay comprising a permanent U-magnet, a bar armature extending between the poles of said magnet and having a transverse axis therebetween, an electro-magnet mounted within the U-magnet and adapted to be selectively energized to effect rotation of the bar armature in either direction on its pivot, and 85 a strip of metal extending longitudinally of the bar armature and secured thereto and having its ends extending beyond the ends of the armature and overhanging the pole ends of the U-magnet in co-operative relation therewith.

3. A polarized relay comprising a U-shaped permanent magnet, an electro-magnet mounted between the arms of said permanent magnet poles, a spindle journaled centrally between the poles of the magnet, an armature rigidly mounted intermediate of its length on said spindle having its respective ends disposed adjacent to the poles of the permanent magnet and having a central portion disposed in influential relation to the end of the core of the electro-magnet, 100 said electro-magnet being adapted to be selectively energized to effect the rotation of the armature in either direction, and stop means for arresting the armature after predetermined movement in either direction.

4. A polarized relay as claimed in claim 2 in which said strip of metal is magnetic and carries non-magnetic buffer pieces for stop contact with the pole ends of the U-magnet to prevent sticking of the armature.
